UNITED STATES PATENT OFFICE.

WILLIAM T. ENGLISH, OF HYDE PARK, MASSACHUSETTS.

INSERT FOR CONCRETE CONSTRUCTION.

1,110,429.

Specification of Letters Patent.

Patented Sept. 15, 1914.

Application filed January 3, 1910. Serial No. 535,950.

To all whom it may concern:

Be it known that I, WILLIAM T. ENGLISH, a citizen of the United States, and resident of Hyde Park, in the county of Norfolk and State of Massachusetts, have invented certain new and useful Improvements in Inserts for Concrete Construction, of which the following is a full, clear, and exact specification.

This invention relates to inserts for use in connection with concrete construction, the object being to provide a suitably hard and firm seat for receiving a nut or the head of a bolt for use in bolting or clamping brackets, hangers, or other parts which are to be removably and yet firmly attached to the surfaces of the concrete.

The concrete itself is generally not sufficiently hard or tough to hold a nut or the head of a bolt. It is moreover difficult to predetermine the exact desired position of any bolt or of a set of bolts. Hence it is desirable to provide an insert, constituting a receiving seat or socket of firm and strong material, preferably of metal, which may be firmly embedded in the concrete during its construction, and which will permit bolts or nuts to be subsequently introduced and allow them a reasonable latitude of lateral adjustment while holding them and their appurtenant objects securely in position when fastened to place.

Figure 1 of the drawings is an end view of one of these inserts, in the form preferred when made of iron or similar metal, illustrating the manner of attaching it in position for embedding it in the concrete. Fig. 2 is a side view of the insert projected from Fig. 1. Fig. 3 is a cross-sectional end view showing the insert embedded in the concrete and showing the head of a bolt in position in the insert. Fig. 4 is a side view projected from Fig. 3, in section taken substantially through the longitudinal center of the insert, illustrating also the manner of inserting the bolt head. Fig. 5 is a face view of the insert, showing a bolt located at one end of the slot.

In the embodiment of this invention illustrated in the accompanying drawings the insert 8 is of a form suitable for being made in cast iron or malleable iron. The body portion is of box-like form having an inner cavity 9 for receiving a nut or the head of a bolt 10. The outer sides 11 of the body are inclined, forming a wedge or keystone

shape for more securely locking it into the concrete. The ends 12 are herein shown to be parallel; but obviously these may also be inclined like a keystone, for added strength or for any other desired purpose. For additional firmness and security the body is provided with an extension, consisting of a base 13 connected with the body in any suitable way, as by the bars 14, suitable spaces being preferably left between and around them for weight distributing rods 16, or to allow the concrete to flow or pack under the base 13, as shown in Figs. 3 and 4. The underneath face 15 of the insert is herein shown to be flat, but obviously it may be curved in any desired way in conformity with the general face of the concrete, or with the surface to be attached to the insert. The face is provided with a slotted aperture 17, of a width suitable for receiving the body 18 of the bolt, this slot, in conjunction with the inner space 9, forming a T-slot which is elongated to any desired extent, according to the amount of adjustment required, or according to the expected variations in setting the inserts in position in the concrete. The inner side walls 19 of the space 9 form guiding surfaces sufficiently close together to prevent the nut or the head of the bolt from turning around when being tightened.

The shoulders 20 at the sides of the slot 17 support the under surfaces of the bolt head or nut, and these shoulders are interrupted at a suitable portion of the slot by means of oppositely disposed recesses 21, to permit the nut or the bolt head to be entered or removed through the face of the insert. The lateral width of these recesses crosswise of the slot 17 is slightly wider than the width of the nut or bolt head to be employed; but their width in a direction lengthwise of the slot is less than the width of the nut or bolt head, so that the latter must be inclined at an angle to its resting position, as shown in Fig. 4, in order to admit it through the recesses. The nut or bolt when turned to its resting position, indicated by the dotted lines in Fig. 4, always rests upon some portion of the shoulders 20, the recessed interruptions being too narrow to allow it to drop out or be drawn out when in that position.

The position of the recesses 21 lengthwise of the slot should be adapted to the working requirements. In the present instance they are shown about midway of the length of

the slot. In some instances, however, it may be found preferable to locate these entering recesses at or near one end of the slot.

In Fig. 1 is shown a method of placing or locating the insert prior to casting the concrete around it. The insert is attached to the inner face of a board 24 or form, which may be a part of the mold or form for defining the face of the concrete. This may conveniently be done by boring a hole through the board at the approximate point where it is desired to locate the bolt which is to be used in the insert. Through this hole a temporary holding bolt 25 is placed, with its head holding the insert in position, clamped to the board or form. Instead of the bolt 25, or in addition thereto, the insert may be provided with projecting ears 26, notched or perforated to receive nails 27 by means of which the insert may be secured to the board 24 or inner face of the form. The reinforcing rods 16, if employed, may then be inserted. After the insert is thus secured, the concrete is put into the form, flowing and packing closely around the insert, as shown in Figs. 3 and 4. After the concrete is set and the form removed, bolts or nuts may be put in place in the insert, as illustrated in Figs. 3 and 4, for attaching hangers, brackets, stringers, or any other structures or objects. The bolts or nuts may be removed at any time, and be replaced by other bolts or nuts. The length of the slot permits the bolt to be adjusted laterally from the approximate position first determined, this being frequently desirable for example in putting up hangers for shafting, to enable any of the hangers to be adjusted into alignment.

The dimensions of the insert may be modified according to the material employed and according to the service required. The face 15 of the insert may be flush with the surface of the concrete, or it may project therefrom. Thus in various ways which will be obvious to those who may make or employ these inserts they may be modified in form, dimensions, and position, to suit different requirements, or different conditions of service.

It being obvious that these inserts may be adapted to receive either a nut, or the head of a bolt, the term "bolt head" which for conciseness is employed in the following claims, is intended to include a nut, and other equivalent shouldered members that may be employed for clamping hangers, stringers, or other objects to the insert.

The reinforcing rods 16 may be of any suitable size, form and material. They may be utilized to assist in locating and holding the insert, while the concrete is being cast around them, and thereafter serve to reinforce the inserts and the surrounding concrete, distributing over a larger area of the concrete the load sustained by the inserts. The rods 16 and the apertures of the inserts through which they pass may be adapted to fit each other more or less closely, according to the requirements. Some of these reinforcing rods may also be used under the outer shoulders or flanges of the base, as also shown in Fig. 1.

I claim as my invention:

1. An insert for concrete construction for removably receiving a bolt head, having shoulders for engaging beneath the bolt head, the continuity of said shoulders being interrupted by oppositely disposed recesses which in the crosswise direction admit the bolt head when inclined and in a direction lengthwise of the shoulders are shorter than the sides of the bolt head, whereby the head of the bolt may be inserted to place through the recesses by inclining the bolt to the direction of the length of the shoulders, and whereby the bolt head when in holding position presents engaging surface to the shoulders longer than the interrupting length of the recesses.

2. A metallic insert for concrete construction, for removably seating and supporting a square-headed bolt, comprising a hollow elongated body having an elongated T slot in its lower face for receiving the bolt head, the supporting shoulders of the T slot being interrupted by oppositely disposed recesses for a portion of their length less than the side of the bolt head, and of a depth sufficient to admit the bolt head transversely of the shoulders, whereby the lower engaging surfaces of the bolt head when in supported position are longer than the recessed interruption in the supporting shoulders, and whereby the bolt can be removed from the insert only by inclining it in a direction lengthwise of the shoulders and withdrawing the opposite edges of the bolt head obliquely through the said recesses.

In testimony whereof I have signed my name to this specification in the presence of two subscribing witnesses.

WILLIAM T. ENGLISH.
